Attorney

UNITED STATES PATENT OFFICE.

HANS HEYNE, OF DRESDEN-BLASEWITZ, GERMANY.

ALARM DEVICE.

Application filed August 20, 1924. Serial No. 733,150.

To all whom it may concern:

Be it known that I, HANS HEYNE, a citizen of the German Republic, residing at Dresden-Blasewitz, Germany, have invented 5 certain new and useful Improvements in Alarm Devices; and I do hereby declare that the following is a full, clear, concise, and exact description of the invention, such as will enable other skilled in the art to which it appertains to make and use the same.

This invention relates to improvements in alarm devices, especially advantageous for use upon motor driven vehicles, having for an object to provide an electrical alarm 15 affectable by climatic or atmospheric conditions, which, when installed upon a motor driven vehicle will function to give immediate alarm with the transmission of but the slightest vibration thereto, as for example, 20 the stepping of a person onto the vehicle running board or into the vehicle, the raising of the motor hood, the cutting of electrical wires or of chains, an attempt to remove accessories, et cetera.

25 It is likewise an object of the invention to provide an alarm of the character mentioned employing means for adjusting the circuit closing means thereof to such a nicety as to regulate the sensitivity of the alarm to vibrations, in order that the period of operation of such alarm may be predetermined.

Other objects of the invention will be in part obvious, and in part pointed out hereinafter.

35 In order that the invention and its mode of operation may be readily understood by persons skilled in the art, I have in the accompanying illustrative drawings, and in the detailed following description based thereupon, set out one possible embodiment of the same.

In these drawings:—

Figure 1 is a fragmentary vertical longitudinal section through the improved alarm;

45 Figure 2 is a vertical transverse section through the same; and,

Figure 3 is a vertical longitudinal section through the tube of the circuit closing device proper.

50 Having more particular reference to the drawings, in connection with which like characters of reference will designate corresponding parts throughout, the improved alarm device may be stated to comprise a casing A constructed of suitable material and supported at its upper end upon the

right angular free extremity of a supporting arm A', said upper portion of the casing having a hanger bracket A² secured to the same, as shown in the Figure 1 and adapted 60 to have pivotal bearing upon the outer portion of the arm A'; as shown in the drawing. A segmental bar S is secured to the lower side of the casing A and is disposed longitudinally of the same; the opposite sides of 65 said bar being adapted to be engaged by the opposed jaws j of the clamping arms n and o, the lower extremities of which are slotted and connected by toggle joint to an operating lever l', which as will be noted, is adapted 70 to be pivoted to a suitable fixed post as indicated at p; a contractile coiled spring s being connected to the outer portion of said lever and to a portion of a fixed object whereby to normally exert a pull to the operating lever l' in order that the opposed 75 jaws of the clamping arms n and o will be in constant engagement with the opposite sides of the segmental arm S. In this way, it will be understood that the casing A will 80 be positively secured in a previously adjusted position with respect to an automobile or other device equipped therewith; the clamping arms n and o when engaged with the opposite sides of the segmental arm S serving 85 to prevent any possible swinging movement of such casing.

A bracket arm b' is fixedly secured within the casing A, as shown in the Figure 1, and has a supporting arm b hinged thereto, as 90 indicated at c; the outer end of such supporting arm being adapted to be engaged by a knob f passed through a segmental slot or way w formed in the adjacent side of said casing A into engagement with the free end 95 of the hinged supporting arm b. In this way, it will be understood that pivotal movement may be imparted to the arm b by moving the knob f upwardly and downwardly 100 through the slot w.

105 Supported upon the upper side of the arm b is an evacuated glass tube a having pockets h and i formed in the lower portion of the same as is clearly shown in the Figure 3, while electrical conductors k and l are molded in the glass of the bottom portions of these pockets and are extended into the tube a as shown. A quantity of mercury or similar electrically conductive material is arranged within the tube a and is adapted to 110 be normally divided into several bodies indicated herein for the purpose of conven-

ience by the reference characters h' and i' , the smaller body i' being normally arranged in the pocket i . Metal straps or similar securing devices are preferably passed about the opposite end portions of the tube a of the circuit closing device proper and are anchored to adjacent portions of the arm b . Thus, displacement or undue movement of the tube a will be absolutely prevented. The electrical conductors k and l , as will be noted, are extended from the casing A of the alarm device into engagement with an audible signalling device, not shown.

With a view towards providing means for securing the hinged arm b in an adjusted position whereby the bodies of mercury h' and i' within the evacuated tube a will be properly relatively positioned, a graduated dial e is mounted adjacent one side of the casing A upon a stub shaft e' rotatably mounted in suitable bearings in an adjacent portion of said casing side; the inner end of the shaft carrying an eccentrically mounted disc d thereupon, the peripheral portion of which is so arranged as to engage with a portion of the under side of the hinged arm b . Thus, it will be understood that with rotation of the dial e , the eccentrically mounted disc d will be rotated, and in consequence, the desired pivotal adjustment of the hinged arm b carrying the circuit closing device of the alarm will be effected, thereby causing the desired spacing of the several bodies of mercury h' and i' in said tube a .

To cushion downward movement of the arm b with release of the knob f whereby displacement of the mercury bodies h' and i' will be prevented, a dash pot g is positioned within the casing A and has the piston p' thereof connected through a link p^2 to the free end portion of the arm b . Thus, with release of the knob f subsequently to the raising of the same within the slot w , it will be understood that return of the same to a position whereat it will engage with the previously adjusted peripheral portion of the disc d will be gradual and therefore, will prevent any possibility of displacement of the mercury bodies h' and i' to such an extent as to cause the same to merge one into another.

The modus operandi of the invention may be stated to be as follows:

Assuming that the device has been attached to a portion of a motor driven vehicle and that the casing A has been properly adjusted and secured in a fixed position through the medium of the clamping arms n and o operated by the lever l' , the several mercury bodies h' and i' are properly adjusted within the tube a , the smaller body i' being received in the pocket i and being spaced for a short distance from the larger body h' , as is clearly shown in the Figure 3. To effect proper placement of the bodies h'

and i' within the several pockets h and i of the evacuated tube a , it is preferable that the hinged arm b be raised to the knob f connected to its free extremity. At this time, the graduated rotatable dial e is adjusted to a position whereby to regulate the sensitivity of the tube a to vibrations which might be subsequently transmitted thereto. During such adjustment of the dial e , it will, of course, be understood that the eccentric disc d will be correspondingly rotated. Upon effecting proper adjustment of the dial e and the disc d , the knob f is released, whereupon the arm b will slowly return to its lower position, engaging the peripheral portion of the adjusted eccentric disc d without further ado, as by manual adjustment or similar tedious details of operation. Abrupt downward movement of the arm b will be prevented by reason of the engagement of the piston p' within the cylinder of the dash pot g , it being understood that such piston p' is connected by a coupling link p^2 to the free portion of said arm b . The circuit closing device of the alarm is now properly set for vibrations of predetermined intensity. Thus, it will be understood that with the transmission of vibrations of sufficient intensity to the casing A of the alarm device, the several spaced mercury bodies h' and i' within the tube a will be displaced, thus causing the same to merge one into the other and in consequence, closing an electrical circuit through the electrical conductors k and l and thereby effecting operation of the audible signal connected to such conductors, hence, giving warning of an attempted theft of the vehicle or of parts or accessories of the same. In this connection, it of course will be understood that the vibration transmitted to the casing A may come from different causes, as for example, the stepping of a person onto the running board of the vehicle or into the vehicle, the raising of the motor hood, cutting of wires or rods or locking devices of the vehicle, an attempted removal of tires from the vehicle or from the spare tire rack or racks of the vehicle or any other attempted theft of accessories of such vehicle.

Manifestly, the construction shown is capable of considerable modification, and such modification as is within the scope of my claims, I consider within the spirit of my invention.

I claim:

1. An electrical alarm device of the character described comprising a casing, an arm hingedly supported within said casing, means extended from said arm without the casing whereby to facilitate pivotal movement of the same, an evacuated glass tube supported on said arm containing a quantity of mercury, said quantity of mercury being adapted to be normally divided into several

spaced bodies, electrical conductors extended into the tube and engaging the several spaced bodies, a dial rotatably mounted adjacent one side wall of the casing, and an eccentrically mounted disc connected to said dial and having the peripheral portion thereof disposed whereby to engage and support said hinged arm.

2. An alarm device of the character described comprising a casing, a movably supported tube therein containing a quantity of mercury adapted to be normally divided

into several spaced bodies, a rotatable dial mounted adjacent one side of the casing, a disc connected to said dial and arranged within the casing having its peripheral portion disposed to engage and adjustably support the said tube, and electrical conductors extending into the tube and engaging the several bodies of mercury therein.

15

In witness whereof I have hereunto set my hand.

HANS HEYNE.
